HOSIERY BOARDING APPARATUS

Thomas Patrick Flanagan, Levittown, Pa.

Application June 20, 1955, Serial No. 516,511

3 Claims. (Cl. 34—103)

This invention relates to hosiery boarding apparatus and has particular reference to the preboarding of hosiery though, as will appear, the apparatus is of more general applicability.

In the manufacture of hosiery from nylon or similar yarns of thermoplastic type the procedure following knitting has involved the successive steps of preboarding, dyeing, and finish boarding. These steps have been required for the production of satisfactory stockings, because of the nature of the thermoplastic yarn. The stockings, as knitted, are full of wrinkles and even if the wrinkles could be otherwise smoothed out the stockings would be very poorly shaped. These thermoplastic yarns are quite stiff and resilient and it is necessary to subject the stockings to a stretched condition on a form and to apply temperatures which will soften and shrink the yarn with the result that upon cooling the stitches are well shaped and a smooth and properly contoured stocking results. The shape thus imparted to the stitches and to the stockings as a whole are thereafter retained unless the stocking is again subjected to a sufficiently high temperature to soften the yarn, which is unlikely in any normal course of laundering since the softening temperature is above the boiling point of water at ordinary pressures. The preboarding as heretofore carried out has been accomplished by the direct application of steam to the stockings and such procedure makes impossible or impractical with the usual dyes a procedure of dyeing before the preboarding, since the moist atmosphere would either destroy the dyes or cause them to run. Accordingly dyeing has followed the preboarding and the stockings following washing have had to be finished by a final boarding operation which essentially involves mere drying, the temperatures used not being sufficient to disturb the stitches which were set as a result of the preboarding operation.

One of the objects of the present invention is to provide improved apparatus applicable to preboarding of the usual type, i.e., preceding dyeing and final boarding. The apparatus is however also applicable to final boarding.

A further object of the invention, however, is to provide a boarding apparatus which may be used following dyeing without preboarding. In this case, the stockings may be dyed as they come from the knitting machine. Then they may be dried and subjected to a single boarding operation in accordance with the invention which will effect the same results as preboarding in setting the stitches and shapes of the stockings but with the result of producing stockings which are in condition for sale. In particular this result is accomplished by carrying out the operation under dry conditions which will not adversely affect the dyes which may have been used.

Further objects of the invention relate to the provision of an apparatus which is convenient to use and rapid in its treatment of the stockings. The apparatus has an automatic cycle of operation giving an operator ample time to remove finished stockings and place unboarded stockings on forms for treatment.

2

The foregoing and other objects of the invention particularly relating to details of construction and operation will become apparent from the following description read in conjunction with the accompanying drawings in which:

- 5 Figure 1 is a side elevation of an improved apparatus provided in accordance with the invention, certain of the parts being shown in section to illustrate details;
- 10 Figure 2 is a view looking in the same direction as that in Figure 1 but showing a vertical section through the apparatus;
- 15 Figure 3 is an end elevation of the apparatus partly in section to show interior details;
- 20 Figure 4 is a fragmentary elevation showing means for attaching a stocking form to a carrier;
- 25 Figure 5 is a fragmentary section taken on the plane indicated at 5—5 in Figure 4; and
- 30 Figure 6 is a wiring diagram showing certain of the electrical connections involved in securing an automatic operating cycle.
- 35 The complete machine comprises a casing generally indicated at 2 formed of sheet metal and structural elements for enclosure of the parts and support thereof. Mounted in the casing is a drive motor 4 which through a magnetic clutch 6 and reduction gearing 8 drives a transverse shaft 10. On one end of this shaft there is secured switch-operating cam 12 which, as most clearly shown in Figure 1, is provided at 45° intervals with lobes 14 and spaces 16. The circumference of the cam is thus divided into eight sections individually corresponding to
- 40 eight stocking forms which are also carried by the shaft as will presently be described. It will of course be obvious that other numbers of stocking forms may be used, in which case the form of the cam 12 would be correspondingly changed.
- 45 The cam 12 acts upon the operating arm 18 of a single-pole double-throw switch 20 which may be of the microswitch type. The clutch 6 is desirably energized by direct current from a rectifier 22 supplied from the conventional alternating current lines.
- 50 The opposite end of the shaft 10 supports a disc-like carrier 24 for the hosiery forms. The carrier 24 is provided with an octagonal flange 26 on which the bases of the forms may rest. At each of eight angularly spaced intervals on the carrier there is provided a square opening 28 receiving the square head of a bolt 30 on which may be threaded a wing nut 32. Each form 34 is provided with a lateral slot 36 which may be slipped over the shank of the bolt to a position in which a hole 40 in the form embraces an associated pin 38 in the carrier. This arrangement provides for easy and secure replacement of forms.
- 55 As viewed in Figures 1 and 2 the top and left-hand sides of the casing 2 are provided with slots 42 affording communication of limited cross-section to the heating chamber 44 provided in the casing and surrounded by heat-insulating material 46. The forms 34 follow an arcuate path in the chamber 44 and to avoid waste space the bottom is desirably delimited by wall portions 48, 50 and 52.
- 60 A blower 53 supplies air through a pair of ducts indicated at 54 and 56 which lead to slotted outlets indicated at 58 on both sides of the path of the forms in the chamber 44. Air driven by the blower is emitted from the slots 58 and passes downwardly across and between two banks of heating coils indicated at 60 and 62 in the form of open resistance wire heaters. As indicated in Figure 2, the coils are desirably arranged so as to take the general shape of an adjacent form occupying the fixed position 34A during a cycle. Reflectors 64 are desirably located back of the heating coils to reflect the maximum amount of heat toward the central region of

chamber 44. The air after passing over the coils 60 and 62 flows toward the left as viewed in Figure 2 and is drawn from the left-hand end of chamber 44 through a vertical slot 66 communicating with a passageway delimited by plates 68 and 70 which leads the air to the intake of the blower 53. A series of guide baffles 72 are desirably provided in this passage to assure that the air intake and hence the flow of air in the chamber 44 is evenly distributed about stockings located on the forms in vertical position during the successive cycles.

The blower 53 is driven by a motor 74 through belt 76, the motor being desirably of variable speed type, the speed being adjustable by means of a conventional control such as indicated at 78 in Figure 1. In this fashion the flow of air and the effective heating may be adjusted.

A pair of timers 80 and 82 are used to control the successive cycles of operation. The cycling controls will be best made clear by consideration of the wiring diagram in Figure 6.

Terminals 84 receiving current from the commercial alternating supply provide through switch 86 current to the rectifier 22 and to the time delay switches 80 and 82. The time delay switches are of the conventional type involving a synchronous timing motor driven by the alternating current together with a clutch arrangement and setting control which provides a cycle following an initiating impulse consisting of a time delay and, at the end of such delay, closure of switches as indicated respectively at 88 and 90. These switches are in parallel and, as indicated in Figure 6, control the supply of current from the rectifier 22 to the magnetic clutch 6. The single-pole double-throw switch 20 is indicated in Figure 6 and it will be noted that it is so arranged as to supply power alternately to the controlling input connections 92 and 94 of the time delay switches.

Each cycle of operation involves rotation of shaft 10 through one-eighth of a revolution followed by a rest period adjustable by adjustment of the timers 80 and 82. In this fashion the forms are brought in succession to various positions of rest which are those indicated in Figure 2. The form extending horizontally to the right in this figure is about to enter the chamber 44, rotation being clockwise. The preceding form in the series is in alignment between the heaters provided by the coils 60 and 62. The next preceding form is in the downwardly extending vertical position where it is subject to the flow of the recirculating air. The next preceding form has been moved out of the end slot in the housing, and the next is in horizontal position extending toward the left where removal and loading may be accomplished.

To understand a cycle, it may be assumed that the switch 20 has just been located in its lowermost position by the action of one of the cam lobes 14. As will finally appear, this will have opened the switch 88 so that the magnetic clutch is deenergized and shaft 10 is at rest despite the fact that the small motor 4 is continuously running. As soon as the lower contact is made by switch 20 the time delay switch 82 has its cycle initiated which involves a predetermined delay, depending on its setting, before the switch 90 therein is closed. When the switch 90 is closed current is supplied to the magnetic clutch to drive the shaft 10. At the end of the one-eighth of a revolution of this shaft the follower 18 will drop off the lobe 14 which it previously engaged causing the switch 20 to close in its upper position. When this occurs current is removed from the switch 82 and its control switch 90 opens deenergizing the clutch and bringing the shaft to rest. At the same time the preset delay cycle of the switch 80 is initiated, and the shaft 10 remains at rest until the end of the delay interval when the switch 88 closes again energizing the clutch 6 to impart another eighth revolution to the shaft 10. At the end of such movement the switch 20 is again shifted

producing opening of switch 88 and restarting the operation of switch 82, thus completing the cycle described.

The rotation of the carrier 10 in each movement is rapid, but the rest periods may be anything desired depending upon the weight of the yarn used in the stocking, the desired action, and the like. In starting operation on a new batch of stockings of a particular type, the operator may make some preliminary tests on a few of them to determine the proper conditions of the rest time to be involved, and of speed of the blower if that is used, and may make adjustments accordingly.

In using the present apparatus for preboarding the flow of air is not used but the preboarding is effected solely by the action of the heaters. Desirably these are of a type in which the total heat is distributed over a considerable area or, in other words, the concentration of heat per unit area is kept low. By control through the timers of the rest periods of the stocking forms proper preboarding is effected.

If the apparatus is used for finish boarding after dyeing and washing, the stockings as they are placed on the forms will generally be damp, and the blower is then used to recirculate air, the rest times of the forms and the blower adjustments being then so made as to effect drying and the proper finish boarding without, however, permitting the temperature to rise to such extent as to reset the yarn. It has been found that in many cases in effecting finish boarding it is desirable to add a second pair of heaters adjacent to the position of the form when it depends vertically from its support, i.e., in the position of the lowermost form in Figure 2. In this way using two pairs of heaters and air circulation effecting proper drying is secured.

In accordance with the invention dyeing may be effected prior to any boarding, the stockings being dyed as they come from the knitting and seaming and looping processes, the dyeing being carried out in accordance with conventional practices followed by washing and drying prior to placement of the stockings on the forms.

The preboarding is then carried out in the fashion indicated above, without the use of recirculating air, the rest times of the cycles being adjusted for proper preboarding. This preboarding is then also the final boarding of the stockings which as taken from the apparatus are in finished condition ready for folding and marketing. It may be noted that in such operation the stockings are not exposed to the preboarding action while wet so that there is avoidance of detriment to the dyeing such as would occur if the heating was carried out under moist conditions.

By reason of the utilization of the recycled hot air very uniform drying is secured, not only of the flat faces of the stockings which are directly opposite the heating coils but of the edges as well.

It will be evident from the foregoing that various changes in details of operation may be effected without departing from the invention. For example, the air flow may be controlled by a damper arrangement with a blower operating at constant speed. Other changes may obviously be made within the scope of the invention as defined in the following claims.

What is claimed is:

1. Boarding apparatus for hosiery comprising an enclosure, means mounting a plurality of hosiery forms for movement into, through and out of said enclosure, means for driving said mounting means intermittently to provide movements of said forms interrupted by rest periods thereof, timing means for adjustably controlling the durations of said rest periods, heating means within said enclosure, and means for recirculating hot air through said enclosure about hosiery carried by forms located therein including a blower, means for conducting air from said blower and discharging the same into said enclosure to one side of said heating means from walls respectively disposed upon opposite sides of the hosiery forms located

within said enclosure, and means for drawing said air across said heating means and enclosure and conducting it to said blower for recirculation thereof.

2. Boarding apparatus for hosiery comprising an enclosure, means mounting a plurality of hosiery forms for movement into, through and out of said enclosure, means for driving said mounting means intermittently to provide movements of said forms interrupted by rest periods thereof, timing means for adjustably controlling the durations of said rest periods, heating means within said enclosure, and means for recirculating hot air through said enclosure about hosiery carried by forms located therein including a blower, means for conducting air from said blower and discharging the same into said enclosure to one side of said heating means, and means for drawing said air across said heating means through an enclosure wall opening having a vertical extent approximating the length of a hosiery form and located on the side of the hosiery form mounting means remote from the heating means and conducting it to said blower for recirculation thereof.

3. Boarding apparatus for hosiery comprising an enclosure, means mounting a plurality of hosiery forms for movement into, through and out of said enclosure, means for driving said mounting means intermittently to provide movements of said forms interrupted by rest periods thereof, timing means for adjustably controlling the durations of said rest periods, heating means within said en-

closure, and means for recirculating hot air through said enclosure about hosiery carried by forms located therein including a blower, means for conducting air from said blower and discharging the same into said enclosure to one side of said heating means, and means for drawing said air across said heating means and enclosure through an enclosure wall opening having a vertical extent approximating the length of a hosiery form and located on the side of the hosiery form mounting means remote from the heating means and conducting it to said blower for recirculation thereof through an air passage intervening said enclosure wall opening and the blower, said air passage being baffled for making the suction induced by said blower substantially equally effective throughout the vertical extent of said opening.
